(57) **CLAIM**

The ornamental design for an LED night-light, as shown and described.

DESCRIPTION

FIG. 1 is a perspective view of the LED night-light showing the invention;

FIG. 2 is a front view of the LED night-light of FIG. 1;
FIG. 3 is a right side view of the LED night-light of FIG. 1, which is a mirror image of the left side view of the LED night-light;

FIG. 4 is a top plan view of the LED night-light of FIG. 1;
FIG. 5 is a bottom plan view of the LED night-light of FIG. 1; and,

FIG. 6 is a rear view of the LED night-light of FIG. 1.

The text shown in broken lines in FIGS. 1-3 and 5 is for illustrative purposes only and is not part of the claimed design.

The electrical plug shown in broken lines in FIGS. 1 and 3-6 is for illustrative purposes only and is not part of the claimed design.

The screw head and accompanying indentation shown in broken lines in FIGS. 4 and 6 is for illustrative purposes only and is not part of the claimed design.

The LED (light emitting diode) light source shown in broken lines in FIGS. 1-4 and 6 is for illustrative purposes only and is not part of the claimed design.

The toggle switch shown in broken lines in FIGS. 1-5 is for illustrative purposes only and is not part of the claimed design.

The upper portion of the housing shown in broken lines in FIGS. 1-4 and 6 is for illustrative purposes only and is not part of the claimed design.

1 Claim, 6 Drawing Sheets

Related U.S. Application Data

continuation of application No. 13/544,365, filed on Jul. 9, 2012, now Pat. No. 8,662,733, which is a continuation of application No. 12/466,209, filed on May 14, 2009, now Pat. No. 5,215,820.
